UNITED STATES PATENT OFFICE.

J. H. BLAISDELL, OF BOSTON, MASSACHUSETTS.

IMPROVED SODA-WATER APPARATUS.

Specification forming part of Letters Patent No 40,811, dated December 8, 1863.

To all whom it may concern:

Be it known that I, JOHN H. BLAISDELL, of Boston, county of Suffolk, and State of Massachusetts, have invented an Improved Soda Apparatus; and I do hereby declare that the following, taken in connection with the drawings which accompany and form part of this specification, is a description of the invention sufficient to enable those skilled in the art to practice it.

My invention relates to improvements in the details and arrangement of soda apparatus by which the manipulation required in preparing beverages is reduced in amount and the quality of the beverage is improved, and by which increased speed of preparing them is attained.

My invention consists in concentrically, or nearly so, arranging around a central orifice or orifices, but separate therefrom, other orifices through which may be drawn sirups or other fluids used in the preparation of effervescent beverages; also, the employment, in a soda apparatus, of a device by which soda may be drawn from one common source through two different deliveries with but one manipulation on the part of the operator; also, the arrangement of two soda passages so that one is within and surrounded by the discharge of the other; also, the formation of a chamber or enlargement in a soda-delivery passage for the purpose of effecting thereby much, if not all, that is obtained in the ordinary way, by the employment of a condensing-bottle, into which the soda is first drawn and afterward decanted.

In the drawings illustrating an apparatus embodying my invention, Figure 1 shows the said apparatus part in plan and part in horizontal section. Fig. 2 shows a rear end elevation; and Fig. 3, a vertical cross section taken in the plane of line $z z$, seen in Figs. 1 and 2.

The part a is divided by partition b into separate passages, which have inlets c and outlets d , which are controlled by puppet-valves e . The outlet terminations of the passages are arranged about a common center, and the valves in these outlets are worked by hand by means of the levers f , rods g , and springs h , the levers f being in the fluids which fill the passages and the rods g passing

through stuffing-boxes, by which leakage is prevented; or the stems of the valves might be continued directly upward through stuffing-boxes, and the levers f might then be placed outside of the passages or pipes which convey the fluids. Within the part a there is a chamber, i , which is located within the circle of or is surrounded by the outlet terminations of the sirup or fluid passages, before referred to. This chamber has a contracted opening, k , within which is the mouth of the soda-discharge pipe l . The chamber i and the pipe l are supplied with soda as follows: The soda-supply pipe m is located above the sirup-pipes e and terminates in an upward direction, with its mouth covered by a diaphragm, n , which rests on a seat, o , confined at its periphery by the piece p , which is chambered out, so as to admit of the piece or washer q and of the upward movement of this and of the diaphragm n . An ornamental device, j , surrounds and surrounds p , serving to cover it and as a bearing or support for the upper end of the spindle r , which has a screw-thread formed on its lower end, which works in a nut formed in p , so that by turning r in one direction by means of the hand-wheel on its end the piece q is forced down on the diaphragm n on the seat o , thus stopping all apertures in o . By turning r in the other direction the pressure on the diaphragm from the screw is relieved, so that the soda under pressure in pipe m lifts the diaphragm and escapes over the seat o through any outlet-passages formed therein. In seat o there is one outlet-passage, s , which connects with pipe l , and there are other outlet-passages, t , which connect with the chamber i and discharge-outlet k . Upon pipe l in chamber i a diaphragm, u , may be fixed, so as nearly to extend across chamber i , the purpose of said diaphragm or collar being to check the flow of the soda toward the outlet k .

In the ordinary practice of preparing soda beverages the sirup is first drawn into a tumbler and then a small quantity of soda is drawn into the tumbler in a fine stream, and under a full head, mixing with the sirup and making a foam or froth. Then from the same soda-outlet or from another a quantity of soda is drawn into a receptacle, sometimes called a "condensing-bottle," and this, without foam or froth, is decanted into the tumbler, making the

bulk of the beverage. Now, by drawing the soda from pipe *m* through several apertures into the chamber *i* the desired quantity of soda is obtained in a quiet condition, and through the pipe *l* enough is obtained moving with sufficient force to mingle thoroughly with the sirup, which comes from any of the sirup-discharge passages *d*, and to form the desired amount of foam, and thus without removal or change of position of the tumbler the beverage is almost instantly prepared by the operator, who has only to rotate the spindle *r* and depress one or more of the rods *g*. Thus less time elapses in preparing a beverage than is required with any other apparatus with which I am acquainted, and the beverage can be passed to the drinker with but little loss of the gases originally contained in the soda. Each of the passages *e* is connected with a separate receptacle for sirup of any desired flavor, cream, wines, cordials, &c., the buttons on the rods *g* being numbered or otherwise marked for the guidance of the operator. It will be evident that when the hand of the operator relieves a rod, *g*, from pressure the spring around that rod will act to close the valve with which that rod is connected.

I claim—

1. In a soda apparatus, the arrangement of one outlet for soda within another, substantially as described.

2. The arrangement around or adjacent to the soda outlet or outlets of the various outlets for sirups and other fluids, substantially as described.

3. The arrangement, in a soda apparatus, of a diaphragm, *n*, and disk *q* or the equivalent thereto, so as to act under pressure, as described, to admit into two or more passages and to shut off therefrom the soda supplied from a common source.

4. The formation of a chamber in a soda-discharge pipe, so as to operate to check the velocity of the discharge under pressure, and thus supersede the employment of the condensing-bottle, substantially as set forth.

5. The condensed arrangement of outlets so that while each is separate from the others they are all within the compass of and can each of them discharge into an ordinary drinking-glass without removal thereof from a fixed position.

J. H. BLAISDELL.
